(57) **CLAIM**

The ornamental design for a bezel setting tool as shown and described.

DESCRIPTION

FIG. 1 is a front, top perspective view showing the new, original, and ornamental design for the bezel setting tool; FIG. 2 is a front elevation view thereof; FIG. 3 is a rear elevation view thereof; FIG. 4 is a right elevation view thereof; FIG. 5 is a left elevation view thereof; FIG. 6 is a top plan view thereof; FIG. 7 is a bottom plan view thereof; and, FIG. 8 is a rear, bottom perspective view thereof. The portions of the bezel setting tool shown in broken line form no part of the claimed design.
